LAWN TRIMMER HOUSING

Leonard B. Goodall, Warrensburg, Mo., assignor to Goodall Equipment, Inc., Minneapolis, Minn., a corporation of Minnesota

Application March 9, 1956, Serial No. 40,528

Term of patent 14 years

(Cl. D40—1)

FIG. 2

FIG. 1

FIG. 3

FIG. 4

Figure 1 is a side elevational view of a lawn trimmer housing showing my new design;

Figure 2 is a top plan view;

Figure 3 is an elevational view taken along the line and in the direction of the arrows 3—3 of Figure 1; and

Figure 4 is an elevational view taken along the line and in the direction of the arrows 4—4 of Figure 1.

The characteristic features of the design reside in the portions shown in full lines.

What is claimed:

The ornamental design for a lawn trimmer housing, as shown and described.
